(57) **CLAIM**

The ornamental design for a tarp cover stop, as shown and described.

DESCRIPTION

FIG. 1 is a front elevational view of a first embodiment of the tarp cover stop of the present disclosure;

FIG. 2 is a rear elevational view of the first embodiment of the tarp cover stop;

FIG. 3 is a top plan view of the first embodiment of the tarp cover stop;

FIG. 4 is a bottom view of the first embodiment of the tarp cover stop;

FIG. 5 is a left side elevational view of the first embodiment of the tarp cover stop;

FIG. 6 is a right side elevational view of the first embodiment of the tarp cover stop; and

FIG. 7 is a perspective view of the first embodiment of the tarp cover stop.

FIG. 8 is a front elevational view of a second embodiment of the tarp cover stop of the present disclosure;

FIG. 9 is a rear elevational view of the second embodiment of the tarp cover stop;

FIG. 10 is a top plan view of the second embodiment of the tarp cover stop;

FIG. 11 is a bottom view of the second embodiment of the tarp cover stop;

FIG. 12 is a left side elevational view of the second embodiment of the tarp cover stop;

FIG. 13 is a right side elevational view of the second embodiment of the tarp cover stop; and,

FIG. 14 is a perspective view of the second embodiment of the tarp cover stop.

Portions of the tarp cover stop that are shown in broken lines form no part of the claimed design.

1 Claim, 14 Drawing Sheets
